UNITED STATES PATENT OFFICE

LILLYMAY LOWERY, OF LOS ANGELES, CALIFORNIA

DESIGN FOR AN AUTOMOBILE RADIATOR CAP OR SIMILAR ARTICLE

Application filed August 4, 1931. Serial No. 40,783. Term of patent 14 years.

To all whom it may concern:

Be it known that I, LILLYMAY LOWERY, a citizen of the United States, residing at 1221 N. Vermont Ave., Los Angeles, in the county of Los Angeles and State of California, have invented a new, original, and ornamental Design for Automobile Radiator Cap or Similar Article, of which the following is a specification, reference being had to the accompanying drawings, forming part thereof.

Figure 1 shows a side elevational view of the automobile radiator cap of my design.

Figure 2 shows a front elevation of the same.

I claim:

The ornamental design for an automobile radiator cap, or similar article as shown.

LILLYMAY LOWERY.
